D. T. ROOT,
ACETYLENE GAS GENERATOR,
APPLICATION FILED DEC. 13, 1916.

1,237,702.

Patented Aug. 21, 1917.

UNITED STATES PATENT OFFICE.

DEWITT T. ROOT, OF FARMDALE, OHIO.

ACETYLENE-GAS GENERATOR.

1,237,702.

Specification of Letters Patent. Patented Aug. 21, 1917.

Application filed December 13, 1916. Serial No. 136,709.

To all whom it may concern:

Be it known that I, DEWITT T. Root, a citizen of the United States, residing at Farmdale, in the county of Trumbull and State of Ohio, have invented certain new and useful Improvements in Acetylene-Gas Generators; and I do hereby declare the following to be a full, clear, and exact description of the invention, such as will enable others skilled in the art to which it appertains to make and use the same.

This invention relates to acetylene gas generators and has for its principal object to provide a simple and efficient mechanism for automatically controlling the feed of carbid.

Another object is the provision of means for adjusting the valve mechanism which feeds the carbid so that the amount of the carbid discharged, when the valve mechanism is automatically operated, is controlled.

A further object is to provide a valve mechanism for feeding the carbid which will automatically adjust itself to allow grains of carbid of different sizes to pass around the same.

A still further object is the provision of an acetylene gas generator in which the parts are so constructed and arranged as to be readily separated to permit cleaning thereof.

With these and other objects in view, the invention consists of the novel construction, arrangement and formation of parts, as will be hereinafter more fully described, claimed and illustrated in the accompanying drawing, in which:

Figure 1 represents a vertical central sectional view through the generator,

Fig. 2 represents a detail sectional view of the valve and adjusting mechanism therefor.

Fig. 3 is a detail plan view of the valve and the supporting bar.

Referring in detail to the drawing, wherein similar reference numerals designate corresponding parts throughout the several views, the numeral 5 indicates a cylindrical liquid container including a bottom 6 and having an opened upper end. A plurality of supports 7 are formed with angularly directed lower extremities engaged upon the upper surface of the container bottom 6 and are secured at said upper end to an inverted frusto-conical carbid holder 8

having an opening 9 in the lower end thereof adapted to be closed by a valve 10 carrying an upwardly extending stem 11. The stem 11 extends upwardly through an aperture 12 in the top of the carbid holder 8 and through a sleeve 13 secured to the top of said carbid holder and carries a cup-shaped plate 14 at its upper end. The valve stem 11 is provided adjacent the upper end 60 thereof with screw-threads on which is fitted a stop collar 15 for variably adjusting the downward movement of the valve 10, said stop collar 15 has a rounded lower portion 16 which is adapted to be swivelly received in the flared top 17 formed on the sleeve 13, when the valve 10 is unseated so that the valve is free to oscillate a certain distance permitting a large piece of carbid to pass by the valve on one side, while a 70 smaller piece is passing by on the other side. Secured to the under face of the top of the carbid holder 8 and around the aperture 12 is an inverted cone-shaped casing 18 which surrounds the valve stem 11 and spaces the 80 carbid therefrom and allows the valve stem 11 to oscillate as hereinbefore described. A circular deflector plate 19 is secured to the bottom of the valve 10 and has the outer edges thereof projecting slightly outward of 85 the valve 10 and has a relatively narrow and horizontally disposed bar 20 secured thereto, which is connected adjacent its ends with the carbid holder 8 by springs 21 normally retaining the valve 10 in closed position. 90

A tray 22 is removably disposed upon the bottom 6 of the liquid container between the supports 7 and is provided with a chain 23 constituting a handle, whereby the tray may be conveniently withdrawn from the container. 95

The liquid container 5 is filled with water approximately to the line designated by the numeral 24 and a bell 25 is fitted within the container and its apron or side wall extends 100 below the water lever as will be understood. The bell 25 surrounds the carbid holder 8, supports 7 and tray 22.

An air exhaust pipe 26 is extended through the side wall of the liquid container 5, and 105 is provided with a valve 27 exteriorly of the container, and is extended downwardly below and in spaced relation to the lower edge of the apron of the bell 25. The inner extremity of the air exhaust pipe 26 is 110 curved downwardly, as at 28, in close relation to the water lever 24. The gas supply

pipe 29 is secured through the wall of the container 5, and is provided with a valve 30 and is extended upwardly within the bell 25 and the opened end 31 thereof terminates 5 above the end 28 of the air exhaust pipe 26.

In use, it will be evident that as the bell 25 lowers due to the fall of the gas pressure therein, the rounded knob 32 carried by the top of the bell will engage and depress the 10 stem 11 together with the valve 10, thus opening the valve and permitting the carbide within the holder 8 to flow over the deflector plate 19 from where it drops into the water contained in the container 5 and into the 15 tray 22. As the carbide enters the water, acetylene gas is generated and the increasing volume thereof elevates the bell 25, disengaging the valve stem 11 and permits the valve 10 to move to closed position under the 20 influence of the springs 21. The air which accumulates within the bell 25 when the generator is not in use may be exhausted through the pipe 26 by opening the valve 27 for a short time after the generator is set in 25 operation.

It is clearly evident that the several parts of the generator may be quickly and conveniently removed from the container 5 to 30 permit thorough cleaning thereof.

What I claim is:

1. An acetylene gas generator including a liquid container, a carbide holder supported in said container having an opening in the lower end thereof, a valve for closing said 35 opening, means normally retaining said valve in closed position, a bell inclosing said carbide holder, a stem projecting upwardly through said carbide holder, a cup-shaped plate carried by the free end of said valve 40 stem, a rounded knob carried by the top of said bell and in direct alinement with said

valve stem and adapted to engage the cup-shaped plate to open said valve, and adjustable means for limiting the opening movement of said valve. 45

2. An acetylene gas generator including a liquid container, a carbide holder supported in said container having an opening in the lower end thereof, a valve for closing said opening, means normally retaining said valve in closed position, a bell inclosing said carbide holder, a stem projecting upwardly through said carbide holder adapted to be engaged by said bell to open said valve, a stop collar adjustably carried by said valve 50 stem adapted to engage the top of said carbide container, whereby the opening movement of said valve is limited.

3. An acetylene gas generator including a liquid container, a carbide holder supported in said container having an opening in the lower end thereof, a valve for closing said opening, means normally retaining said valve in closed position, a bell inclosing said carbide holder, a stem projecting upwardly through said carbide holder adapted to be engaged by said bell to open said valve, a sleeve having a flared top secured to the top of said carbide holder and having the bore thereof registering with said aperture, a stop collar adjustably carried by said valve stem, said stop collar having a rounded end adapted to fit in the flared end of said sleeve, whereby said valve stem is free to oscillate, so that different sized pieces of carbide may 70 pass around said valve. 75

In testimony whereof I affix my signature in presence of two witnesses.

DEWITT T. ROOT.
